HENRY L. DOHERTY, OF NEW YORK, N. Y.

PROCESS FOR PRODUCING A DIFFUSED FLAME WITH PRODUCER-GAS.

1,206,821.

Specification of Letters Patent. Patented Dec. 5, 1916.

Application filed May 15, 1911, Serial No. 627,134. Renewed March 11, 1916. Serial No. 83,675.

To all whom it may concern:

Be it known that I, HENRY L. DOHERTY, a citizen of the United States, and a resident of New York city, in the county of New York and State of New York, have invented certain new and useful Improvements in Processes for Producing a Diffused Flame with Producer-Gas, of which the following is a specification.

10 This invention relates to a process for producing a diffused flame with producer gas.

The object of my invention is to make possible the burning of producer gas in a furnace (a retort oven for the manufacture of coal gas for instance) with a prolonged, diffuse flame whereby the whole charge of the furnace may be bathed in a flame of approximately uniform temperature, and thus a uniform heating effect secured throughout the furnace.

Briefly stated, my invention consists in diluting producer gas with some inert non-combustible gas (preferably, products of combustion) to an extent which will insure the production of a flame of the character desired. The effect of this is to greatly reduce the velocity of reaction at the place of mixture of the producer gas and air. The combustible constituents of the producer gas being diluted with a comparatively large volume of diluent gases their combustion is retarded and the gas thus caused to burn with a prolonged flame which is made extra voluminous by the presence of the diluent gases. As a consequence of this, combustion of the gas takes place throughout a much larger region of the retort oven, or other furnace, than is the case when the gas is burned without dilution. In fact, the proportion of diluent gas may be so adjusted that combustion will not be completed until just before the gases discharge from the oven. The result of this is that I am able to bathe each and every one of the retorts in the oven chamber with a flame of burning gas of just the right temperature to secure the best results in carbonization. Instead of confining the heating by direct radiation to the inner sides of the retorts in immediate contact with the comparatively small region usually occupied by the flame, I am able, by my invention to practically fill the retort oven with a slow burning heat-radiating flame. The result is that I am able to bathe each

and every one of the retorts in the oven chamber with a flame of burning gas of just the right temperature to secure the best results in carbonization. The heating of the charges in the several retorts is thus made very uniform. Besides this advantage, I secure another important result—i. e., increased life of the retorts and setting due to the possibility of working with a uniform and moderate temperature. Each retort is exposed to only the temperature that is required for perfect carbonization. It is not necessary to overheat some retorts in order to properly heat the remainder.

In the drawings I have shown an apparatus capable of carrying out my improved process.

Figure 1 is a longitudinal section through the middle line of the furnace (A—B of Fig. 2.) Fig. 2 is a half cross-section on the line C—D of Fig. 1 and half elevation of the apparatus.

The method of operating the apparatus is as follows: A comparatively deep bed of fuel is maintained in the gas producer 1, the fuel bed being supported by the grate 2. The combustion of the fuel is supported by air admitted through the damper 3. Drip plates 4 are placed in the front of the producer, to which water is supplied through the pipe 5. The water runs onto the uppermost drip plate and thence the excess passes from plate to plate, the drip from the lower plate falling into the water pan 4' beneath the grate. The heat of the fuel bed evaporates the water in the pans 4, the vapor produced passing into the fuel bed and cooling the same. In the ash zone of the producer just above the grate 2, the cooling effect of the vapor is due chiefly to the absorption of sensible heat by the vapor from the ash. In the upper part of the fuel bed the cooling effect is due to the heat taken up from the incandescent fuel and rendered latent through the reaction between the water vapor and the incandescent carbon, viz.— $H_2O + C = H_2 + CO$. The oxygen of the air admitted also reacts with the fuel to produce carbon monoxide according to the well known producer reaction, $C + O = CO$. The producer gas thus generated ascends from the fuel bed and, in the usual method of operation, passes through the nostrils 6 into the oven chamber 7, where it is burned by the preheated air entering through the air nostrils 8. This air enters the recuperators

9 and 10 through the air passages 11 and 12, respectively, and passes upward through the flues 13, in which are located the combustion gas flues 15. Passing in contact with the flues 15 the air is highly heated and discharges through the nostrils 8. The producer gas and air burn with a relatively short hot flame, the combustion usually being completed within the combustion chamber formed by 10 the retorts and arch of the oven. There is thus a relatively high temperature developed along the inner walls of the retorts, while the outer walls of the same are in contact with much cooler gases which have been 15 cooled by contact with the walls of the retorts themselves. The products of the combustion of the gas pass through the ports 16 of the uppermost of the flues 15 in each recuperator and thence through the flues 15 20 and flues 22' and 22" to the stack 22. In passing through flues 15 the gases give up a large part of their sensible heat to the air ascending through the enveloping flues 13.

According to my invention, I modify the 25 above-described method of operation by introducing into the producer gas a portion of the combustion gases discharged from the oven. I accomplish this by the injector 17.

This is provided with a nozzle 18 to which 30 steam is admitted from the pipe 19 by manipulating the valve 20. The steam jet discharging through the injector nozzle or passage 18 induces a flow of combustion gases through passages 21 (one on each side 35 of the oven) which communicate with the front ends of the uppermost of the flues 15. By using the steam at a fairly high pressure, it is possible to introduce a relatively large volume of combustion gases with a 40 comparatively small volume of steam.

The mixed combustion gases and steam pass into the space in the producer chamber 1 above the fuel bed and mix with the producer gas which is arising from the latter. 45 The inert combustion gases dilute the combustible constituents of the producer gas so that the normal flame of undiluted gas is greatly lengthened, and diluted. By using the proper proportion of inert gas the combustion of the producer gas may be made so 50 slow that complete combustion will not have taken place until the gaseous mixture has reached the points of discharge from the oven. The proportion of combustion gases to producer gas may be varied from 1 to 19 to 1 to 1 according to the size of the furnace, the character of the flame and the flame temperature desired by regulating the 55 pressure of the steam and regulating the volume admitted from pipe 19 by the adjustment of valve 20. By taking samples of the gas from the chamber 1 just below the nostrils 8 and of the combustion gases and analyzing them, the proportion of combustion gases introduced for any setting of

the valve 20 may be readily ascertained with sufficient accuracy. Usually, however, the adjustment of valve 20 may be regulated by an experienced operator by the appearance of the flame filling chamber 7 without having recourse to analysis of the gases. With a furnace of the kind shown, I usually prefer to use a volume of combustion gases equal to about one-half of the volume of the producer gas, measured at the same temperature and pressure. With this proportion of combustion or flue gases the combustion of the producer gas is caused to take place at a slow and uniform rate so that the loss of heat from the gases to the retorts is 70 being constantly corrected by further combustion of producer gas. In this way I am able to substantially fill the retort chamber or oven with a flame of comparatively uniform and constant temperature, slow combustion taking place throughout the body of a fairly homogeneous gas mixture. The retorts are thus enveloped in an atmosphere of uniform temperature which insures a 75 regular and even heating of the charge. This, in turn, insures a uniform quality in the gas and coke produced as well as improves the average quality of both.

A further advantage of my invention is that the uniformity of the temperature carried throughout the bench greatly adds to the life of the same by avoiding the unequal expansion of the interior structure, due to marked inequalities of temperature, which result in the formation of cracks.

Having described my invention, what I claim is:

1. In the heating of furnace chambers, the process of regulating flame temperatures which comprises diluting producer gas with a proportion of non-combustible gas, introducing said mixture into a furnace chamber and burning said mixture in said chamber by means of a current of air.

2. The method of regulating the temperature of combustion of producer gas which comprises, diluting the said producer gas with gases of substantially complete combustion, adding air to the resulting diluted gas, and burning the resulting mixture in such manner as to produce a diffused combustion.

3. The method of securing a substantially uniform flame temperature in a producer-gas-fired-furnace which comprises diluting the producer gas with non-combustible gases to give a gas of relatively low calorific value, introducing the resulting diluted gas into said furnace, and introducing air into said furnace, to burn the said diluted gas with the production of a slow-burning flame of moderate temperature.

4. The method of securing a uniform heating effect in a furnace chamber which is maintained at an igniting temperature which comprises, generating a producer gas,

mixing non-combustible gases with the said producer gas, introducing the resulting mixture into the said furnace chamber, and introducing air into the said chamber, where-
5 by the said gas is caused to burn with a voluminous, slow-burning flame that substantially fills the said chamber.

5. The process of securing a uniform heating effect in a furnace chamber which com-
10 prises generating a producer gas, mixing with said gas a volume of combustion gases to the extent of between 5 to 100 per cent. of the volume of said gas, introducing the resulting weak combustible gas into the said
15 furnace chamber, preheating air, and introducing said preheated air into said furnace chamber, whereby the said weak gas is caused to burn with a slow-burning voluminous flame which substantially fills said
20 chamber.

6. The process of heating a furnace chamber which comprises generating a producer gas, mixing with said gas a volume of combustion gases to the extent of between 5 to
25 100 per cent. of the volume of said gas, introducing the resulting weak combustible gas into the said furnace chamber, preheat-
30 ing air by transferring thereto a portion of the heat of the combustion gases from said furnace chamber, and introducing said pre-
35 heated air into said chamber, whereby the mixture of producer gas and combustion gases is burned with the production of a voluminous slow-burning flame whose length may be regulated by varying the proportion of combustion gases in said mixture within the limits given.

7. The method of regulating the tempera-
ture of combustion of combustible gas which

comprises, diluting the said combustible gas 40 with a mixture of gaseous products of combustion and steam to give a lean gas of relatively low calorific value, and burning the said lean gas in contact with heated refractory material by heated air.
45

8. The process of heating a furnace chamber which comprises, generating producer gas, diluting the said producer gas by mixing therewith non-combustible combustion-retarding gases in such volume that the combustion of said producer gas will be pro-
50 longed throughout said furnace chamber, adding to the diluted producer gas in said chamber a sufficient volume of air to effect complete combustion of the said diluted gas,
55 igniting the resulting gaseous mixture and conducting the burning mixture through said furnace chamber.

9. The process of heating producer gas fired gas benches having a combustion chamber with retorts therein, which comprises re-
generating producer gas by a suitable draft current passed through a mass of ignited fuel, mingling with said gas beyond said mass hot returned products of combustion 60 from the combustion chamber, passing the mixture into the combustion chamber and there burning it with heated air around said retorts, a portion of the hot products of
65 combustion thereby produced being returned 70 for admixture with more producer gas.

Signed at New York city, in the county of New York and State of New York this 13th day of May, A. D. 1911.
